POLE BASE

Filed Oct. 12, 1927

Inventor
William R. Rutherford

By Herbert C. Smith

Attorney

UNITED STATES PATENT OFFICE.

WILLIAM R. RUTHERFORD, OF SPOKANE, WASHINGTON.

POLE BASE.

Application filed October 12, 1927. Serial No. 225,672.

My present invention relates to an improved pole base which is designed for the purpose of supporting telegraph poles, light poles, and poles for supporting power lines, 5 as well as for other purposes. The device is designed to elevate the base or butt end of the pole and support it above the ground line in order that deterioration of the pole may be eliminated, and of course the durability of 10 the pole is increased. As is well known, the wooden poles decay from dry rot or from other causes and require replacing at frequent intervals. The device of my invention is designed to eliminate the frequent replacement 15 of the poles, and the base of my invention may be employed in connection with poles that have previously been in use, by sawing off the butt end of the pole that may have been ruined.

20 The invention consists in certain novel combinations and arrangements of parts as will hereinafter be more fully disclosed and claimed.

In the accompanying drawings, I have 25 illustrated one complete example of the physical embodiment of my invention wherein the parts are combined and arranged according to the best mode I have so far devised for the practical application of the principles of my 30 invention.

Figure 1 illustrates a telephone or telegraph pole supported by one of the bases of my invention;

Fig. 2 is a sectional detail view at line 2—2 35 of Fig. 1;

Fig. 3 is a vertical sectional view as at line 3—3 of Fig. 2;

Fig. 4 is a detail view of the hinged supporting bar or upright of the base;

40 Fig. 5 is a plan view of one of the retaining rings; and

Fig. 6 is a detail sectional view showing the manner of wedging the rings to the upright bars.

45 In order that the general arrangement and relation of parts may readily be understood I have shown in Fig. 1 a pole P having the usual cross arms C and the base B supports the butt end or lower end of the pole 50 above the ground line G.

The base is preferably made up of cement concrete and is fashioned with a central opening H to economize in the use of material. The base may be of any approved shape in

horizontal cross section, and it is preferably 55 fashioned with a circular seat 1 in the top in which the butt end of the pole is seated and then tar or other water proofing material is poured into this seat around the bottom of the pole to make a close joint and prevent 60 moisture from having access to the bottom of the pole.

The base B is fashioned with a suitable 65 number of rigid uprights or retaining bars 2. Three of these bars are shown in the drawing, and a fourth bar as 4 is also used. These four bars are arranged at diametrically opposite points and each bar is fashioned from channel irons with flanges 3. The bars are arranged to enclose the butt end of the pole 70 with the free edges of the flanges pointing outwardly, or radiating from the center of the pole. The channel bar 4 is hinged to a base section 5 at 6, and the base section 5 is embedded in the concrete base B. It will be 75 understood of course that the lower ends of the bars 3 are also embedded in the concrete base B and they are rigidly held in this manner. In order to reinforce this structure, I may employ a number of horizontally disposed reinforcing rings 7 in the base that 80 encircle the four uprights, and in addition to holding the uprights in position these reinforcing rings strengthen the concrete base.

The hinged bar 4 is turned down to dotted 85 line position in Fig. 3 when the pole is to be erected, and the butt end of the pole is slipped into its seat between the three rigid bars or uprights 2, then the pole is turned to upright position, and the hinged bar 4 is turned to 90 upright position. The bars are adjusted in approximate position to frictionally engage the exterior surface of the butt end of the pole, but means are provided for making a 95 positive engagement of these upright bars with the pole as follows.

Before the pole is erected, a number of rings as 8 (here shown as 3) are slipped over the pole from either end, and these metal rings are provided with flanges as 9. Each 100 ring, at diametrically opposite points, is provided with a pair of spaced slots 10 which extend a sufficient distance in the ring 8 to form tongues 11. These slots and tongues conform to the shape of the channel bars 2 and 4 and it will be apparent that the tongues are designed to slide down in the channels of 105 the bars, while the slots accommodate the

flanges 3 of the bars. The retaining rings 8 are forced down by repeated blows from a suitable tool or machine, and the tongues 11 assume the position illustrated in Fig. 6 and 5 perform the function of wedges for the purpose of forcing the upright arms into contact with the exterior surface of the butt end or base of the pole. Should the pole have an irregular surface, the irregularity may be 10 compensated for by using a shim or cutting off any protuberances on the exterior surface of the pole.

In Fig. 3, the upright bars are indicated as 12 and they are offset from their lower 15 ends 13, which lower ends are embedded in the base B. In some instances, the uprights may be fashioned in this manner when it is desired to increase the size of the socket of the base to receive a large pole, without necessarily increasing the diameter of the base B. 20

Having thus fully described my invention, what I claim as new and desire to secure by Letters Patent is—

1. The combination with a base, of a series of fixed channel iron bars, a hinged channel 25 iron bar, a retaining ring adapted to encircle said bars, said ring having slots to accommodate the channel irons, and tongues to perform the functions of wedges for the purpose described. 30

2. The combination with a base, of a series of fixed upright bars having outwardly projecting pairs of spaced flanges, and one of said bars having a hinge joint, of a continuous retaining member surrounding said upright bars, and tongues on said retaining member frictionally engaging said bars between said pairs of flanges. 35

In testimony whereof I affix my signature.

WILLIAM R. RUTHERFORD.
